UNITED STATES PATENT OFFICE.

WILLIAM WENDERHOLD, OF NEW YORK, N. Y., ASSIGNOR TO CRU PATENTS CORPORATION, A CORPORATION OF NEW YORK.

FILM-GUIDE.

1,334,338.

Specification of Letters Patent. Patented Mar. 23, 1920.

Application filed September 19, 1917, Serial No. 192,072. Renewed August 20, 1919. Serial No. 318,767.

To all whom it may concern:

Be it known that I, WILLIAM WENDERHOLD, a citizen of the United States, residing at New York city, in the county and State of New York, have invented certain new and useful Improvements in Film-Guides, of which the following is a clear, full, and exact description.

This invention relates to film guides and especially to means that will guide a film tape around feed rollers.

The object of my invention is to provide a frictionless flexible guide that is able to conform to or follow any curvature. Heretofore the applied devices consisted either of a brake shoe or of rollers mounted in non-flexible brackets. I have therefore devised a new form of guide which will be more clearly described hereafter.

20 Referring to the drawing:

Figure 1 is a side elevation of a projecting apparatus containing my guides;

Fig. 2 is a cross-section through the guiding means;

25 Fig. 3 is a front view of the guide means;

Fig. 4 is a view of the guide chains.

As shown in Fig. 1, the film F passes around the feed rollers 1 and 2. Thereafter it passes around the usual intermittently 30 driven feed roller 3 and thereafter over the lower feed roller 4.

In my drawings I have illustrated my guide means around the roller 3 only, but it can be applied to any of the rollers, and 35 also for straight guides.

My guide means consist of a chain of rollers connected with each other by links 6, the rollers being larger in diameter than the width of the links so that all surfaces in contact with the film are rolling around their

individual pivot 7. The chains themselves are stationary, hanging on one extremity in a suitable support 8. On the other end they terminate pivotally on a yoke 9, which yoke is again pivoted in its center upon a slidably 45 mounted bar 10, which bar slides in the support 8 and is pushed forward by the compression spring 11 around the limit screw 12. The spring is compressed by the adjustment nut 13. It is now easily understood 50 that this roller guide is able to conform to the shape of any feed roller against which it is pressed by means of spring 11. Very great pressure can be brought to bear against the film without said guides acting 55 as a brake and causing wear on the film, as the guide means now in use do, and therefore my invention is a great improvement over existing devices for this purpose.

I claim as my invention:

1. In a motion picture device, a guide means for a film consisting of rollers mounted in links, said links being connected with each other, and a support for the links at one extremity and a yoke on the other extremity, a pivot member supporting said yoke, and a spring providing tension for said yoke, and links, as and for the purpose described. 60

2. In a motion picture device, a guide for 70 a film consisting of a roller chain, a support to hold said chain in position, and means to hold said chain flexibly in contact with a film, means to bring pressure upon said guide, and means to adjust said pressure, as 75 and for the purpose described.

Signed at the city of New York, New York, this 12th day of September, one thousand nine hundred and seventeen.

WILLIAM WENDERHOLD.
